UNITED STATES PATENT OFFICE.

MAX SHEAR, OF KANSAS CITY, MISSOURI.

ADJUSTABLE FOOT REST FOR SHOE-SHINING STANDS.

Application filed July 9, 1926. Serial No. 121,379.

This invention relates to shoe-shining stand equipment and has for its object to produce an improved foot support of the type which may be quickly and easily moved 5 from operative to inoperative position in order to free the steps from any obstructions interfering with the safe mounting of a customer.

Another object is to produce a foot rest 10 which may be readily adjusted by means of a double sliding adjustment to accommodate the length of leg of the occupant of the stand so that the foot rests may be in convenient position.

15 With the general objects named in view, the invention consists in certain novel and useful combinations of parts as hereinafter described and claimed; and in order that it may be fully understood, reference is to be 20 had to the accompanying drawings, in which:—

Figure 1 illustrates a section taken through a shoe-shining stand embodying the invention.

25 Figure 2 is a front view of the same.

Figure 3 is a top plan view of the adjustable foot rests with the chair legs illustrated in section.

Figure 4 is a section similar to Figure 1 30 but illustrating a modified form of the invention.

Figure 5 is a front view of the structure shown in Figure 4.

Figure 6 is an enlarged detail side elevation of the adjustable foot rest as shown in Figures 4 and 5.

Figure 7 is a front view of the same.

Figure 8 is an enlarged section on the line VIII—VIII of Figure 6.

40 Figure 9 is an enlarged section on the line IX—IX of Figure 4.

Figure 10 is an enlarged perspective of a modified guide forming a part of the invention.

45 In the said drawings where like reference characters identify corresponding parts in all of the figures, 1 indicates a stand of rectangular outline and of suitable height on which is mounted a chair 2 for occupancy by the patron. In order that the top 3 of the stand 1 may be readily and easily attained by the customer, a suitable step 4 is provided, end edges of said step being slidably received within a pair of guide 50 channels 5 carried by the side walls of the stand. It will be apparent that when the

stand is not in use and it is desired to secure more floor space, the steps may be quickly slid into the stand.

In the form of the invention shown in 60 Figures 1, 2 and 3, two pairs of guides 6 are secured to the top of the stand underneath the chair and form tracks or retaining guides for the sliding reception of the cross heads of inverted T-iron slides 7 of such length 65 as to project slightly beyond the front end of the stand when in operative position. In order to prevent the accidental withdrawal of the slides 7 from the guides 6, each of said slides is formed with a stud 7 at its 70 rear end which abuts against the ends of the guides as illustrated in Figures 1 and 3. The stem or main leg of the T-shaped slides are provided with longitudinal slots 8 adja- 75 cent their front ends.

The front ends of the main leg or stem of the slides are received between the bifurcated arms 9 of suitable foot supports 10. To retain said foot supports 10 in any desired position of adjustment the rear ends 80 of the arms are provided with clamp bolts 11 passing through the slots 8 in the slides 7 whereby the foot supports may be clamped at the desired position of extension to accommodate the patron. 85

The arms 9 of the foot supports are formed along their top and bottom edges with registering undercut bayonet notches 12, the lower notches 12 being adapted to engage a cross pin 13 carried by the slides 90 to assist the clamp bolts 11 in retaining the foot supports in any predetermined position.

When it is desired to move the foot rest to inoperative position, it will be evident that the operator will loosen the clamp bolt 95 11 and then will simultaneously move the foot support 10 rearwardly and upwardly to disengage the notch 12 from the pin 13, and then will slide the foot support rearwardly along the slot 8 until the bolt 11 contacts with the rear end of the slot. Continued inward movement will completely remove the foot rest to its inoperative position beneath the chair as shown in dotted lines (Figure 1) by effecting the rearward sliding movement of slides 7. It will be apparent that a reversal of the above operations are effected to withdraw the foot supports to their operative positions. 100

105 The construction of the modified form of foot rest shown in Figures 4 to 9 inclusive is the same in all respects to that above- 110

described. The method of assembly and operation, however, is slightly different, as follows:—The guides 6 are secured to the underside of the top of the cabinet, and the slides 7 are engaged with the slots in upright position as shown in the drawings. In this construction the pin 13 engages the upper bayonet notches 12 and not only assist the clamp bolts 11 in preventing longitudinal movement of the foot rests, but also support the rests against their natural gravitational tendency to move downwardly. In this construction, when it is desired to move the foot rest to inoperative position, the clamp bolt 11 is loosened as above described, and then the foot rest 10 is simultaneously moved rearwardly and downwardly to disengage the notch 12 from the pin 13. The foot rests then slide rearwardly as described and are permitted to rest on top of the step 4 in their inoperative position as shown clearly in Figure 4 in dotted lines.

Figure 10 illustrates a slightly modified form of guide consisting of a flat plate 14 to rest against the surface of the stand, and on which a pair of side flanges 15, similar to the guides 6 are formed, for the reception of the cross-head of the T-shaped slides 7.

From the above description, it will be apparent that while I have described and claimed the preferred embodiment of the invention, it is to be understood that I reserve the right to make all changes properly falling within the spirit and scope of the appended claims.

I claim:

1. In a shoe shining stand, a chair supporting platform, a guide secured to the

platform, a slide structure comprising telescopically extensible sections mounted for longitudinal movement within the guide and transversely of the stand, a stop for preventing undue forward movement of the slide sections, and a foot rest carried by the forward end of one of the slide sections. 40 45

2. In a shoe shining stand, a chair supporting platform, a guide secured to the platform, a slide member mounted for longitudinal movement within the guide and transversely of the stand, a stop for preventing undue forward movement of the slide member, a foot support arm having sliding engagement with the front end of the slide member, means for securing said support arm to said slide in various adjusted positions, and a foot support carried by said arm. 50 55

3. In a shoe shining stand, a chair supporting platform, a guide secured to the platform, a slide mounted for longitudinal movement within the guide and transversely of the stand, a stop for preventing undue forward movement of the slide, a foot support arm formed with a notch in its edge and having sliding engagement with the front end of the slide, a clamp for securing said support arm to said slide in adjusted position, a pin carried by said slide for engagement with said arm notch to cooperate with the clamp in securing the arm in predetermined position, and a foot support carried by said arm. 60 65 70

In witness whereof I hereunto affix my signature.

MAX SHEAR.
